UNITED STATES PATENT OFFICE.

HARRY R. BARR, OF PHILADELPHIA, PENNSYLVANIA, ASSIGNOR OF ONE-THIRD TO CHRISTIAN BOYD ZACHARIAS AND ONE-THIRD TO WAYNE E. BYERS, BOTH OF CHAMBERSBURG, PENNSYLVANIA.

VANITY CASE.

Application filed January 24, 1923. Serial No. 614,583.

To all whom it may concern:

Be it known that HARRY R. BARR, a citizen of the United States, residing at Philadelphia, in the county of Philadelphia and 5 State of Pennsylvania, has invented certain new and useful Improvements in Vanity Cases, of which the following is a specification.

This invention relates to vanity cases, 10 and more particularly to receptacles having a mirror and adapted to contain compacts of toilet preparations, such as powder and rouge, and pads or puffs for applying them.

One of the objects of the invention is to 15 provide a simple construction of this kind in which the mirror and powder and rouge may all be accessible at the same time, and may be conveniently and readily used.

Another object of the invention is to provide simple and effective means for retaining 20 the compacts of rouge and powder in place and means for retaining a rouge puff or pad on its compact.

Still further objects of the invention and 25 details of construction will be apparent from the following specification when taken together with the accompanying drawings, in which:

Figure 1 is a perspective view showing a 30 vanity case embodying the invention, the parts being shown in closed position.

Fig. 2 is a perspective view of the case shown in Fig. 1, with the parts positioned so that the case is open and ready for use, 35 and with the rouge and powder puffs in place.

Fig. 3 is a central vertical sectional view of the structure shown in Fig. 1.

Fig. 4 is a partial perspective view similar to Fig. 1, but showing a modified form 40 of latch for holding the mirror in closed position.

Fig. 5 is a detail view in perspective of a member for latching the compact-receiving 45 compartments together.

Fig. 6 is a perspective view of another structure embodying the invention.

Fig. 7 is a perspective view of the structure shown in Fig. 6 with the mirror in 50 extended position.

Fig. 8 is a sectional view taken on line 8-8 of Fig. 6.

Fig. 9 is a sectional view taken on line 9-9 of Fig. 6.

Fig. 10 is a central vertical sectional view 55 of another embodiment of the invention.

Fig. 11 is a horizontal sectional view taken on line 11-11 of Fig. 10, showing the bottom of the mirror.

Fig. 12 is a detail view in perspective of 60 the structure of the mirror latch shown in Figs. 10 and 11.

Fig. 13 is a plan view of the rouge puff shown in Fig. 10, and

Fig. 14 is a detail view in perspective 65 showing another form of mirror latch.

As shown in Figs. 1 to 3, the vanity case comprises an upper compartment 11 and a lower compartment 12 connected by a hinge 13, the parts of which are welded or otherwise suitably secured to the compartments. The lower compartment is preferably formed with a circumferential bead 14 near its upper edge to limit the closing movement of the upper compartment, the 70 bead 14 being broken to receive the hinge, as shown in Fig. 3, and the hinge is positioned with its pivot pin slightly below the edge of the lower compartment 12.

A mirror 15 is carried in a frame 16 which 80 covers the back of the mirror and is provided with a circumferential flange 17 which is turned over to hold the mirror in place, and the mirror 15, with its frame, is pivotally secured to the upper compartment 85

12 by a pivot pin 18, shown in Fig. 5, which has a T-head 19 held between the body of the frame 16 and its inturned flange 17 and, if desired, soldered or welded in place. The body of the pin 18 projects through the top 90

wall of compartment 11 and is secured in place by a metal strap 20, bent partly around a reduced neck 21 of the pin and having its ends 22 welded or otherwise suitably secured to the inner wall of the upper compartment 11. The end of the pin 18 is formed with a lateral projection 23 adapted to engage in the recess in the lower compartment formed by the bead 14 to lock the 95

compartments together in closed position.

A rouge compact 24 is held in the upper compartment by a split ring 25 of sheet metal which is sprung into the compartment and resiliently engages the lateral wall there- 100

of, and a portion of the ring 25 is struck up to form an integral resilient finger 26 under which a rouge-pad may be pushed and be thereby retained in contact with the com- 105

pact. A powder compact 28 is similarly retained in the lower compartment by a split ring 29 of sheet metal which, as shown in Fig. 3, may be of U-shape in cross-section to provide for access to a maximum surface of the compact and for greater frictional engagement with the wall of the compartment. A powder puff or pad 30 is provided to fit in the lower compartment 12, but as the compartment is in substantially horizontal position when the case is in use it is not preferable or necessary to provide means on the ring 29 to hold the puff 30 in place.

The upper compartment is provided with a projection 31 which fits in a recess 32 in the edge of the mirror frame 16 when the frame is in registration with the upper compartment, as shown in Fig. 1, and which, when the mirror and frame are swung to extended position as shown in Fig. 2, is engaged by the edge of the frame and limits its movement. A slight depression 33 is made in the edge of the mirror or frame away from its pivot point, adapted to receive a tongue 34 on the hinge 13, and preferably integral therewith, to yieldingly latch the mirror in register with the back of the upper compartment.

In the modified form of latch shown in Fig. 4, the mirror or frame is cut away as shown at 35, and the upper member of the hinge 13 is bent over into the plane of the frame, such member and the frame being formed with opposed circumferential projections 36 and 37 which are slightly hook-shaped and interlock to latch the parts together.

In the modified form shown in Figs. 6 to 9, a vanity case of rectangular shape is formed of upper and lower compartments 38 and 39 connected by a hinge 40 and limited in their telescopic movement by a bead 41 on the lower compartment. The upper compartment is formed with grooves 42 adjacent its upper edge, such grooves extending from a point adjacent one end of the compartment to a point adjacent the other end thereof. A mirror 43 is carried in a frame 44, of the same contour as the compartment 38 and having its edge folded over to hold the mirror in place and space the mirror slightly from the top of the upper compartment. Near its end adjacent the hinge, the frame 44 is provided with fingers 45 which engage in the grooves 42 to retain the mirror upon the compartment 38 and limit its sliding movement thereon in either direction. Rouge and powder compacts are held in place in the compartments 38 and 39 by split rings 46 and 47, similar to rings 25 and 29 shown in Figs. 2 and 3, but shaped to fit within the compartments.

In the modification shown in Figs. 10 and 11, a round upper compartment 48 is hinged to a round lower compartment 49 at 50,

and a recess 51 is formed in the upper compartment to receive a projection 52 on the lower compartment to latch them together. A mirror 53 is removably held by a flat split ring 54 in a frame 55, such frame having an inturned flange 56 between which and the mirror the ring 54 engages. A pin 57, having a T-head 58 secured between the body of the frame 55 and its flange 56, projects into the compartment 48 and is pivotally secured to the wall of the compartment by a strap 59 which extends about the pin between an enlargement 60 at its end and the top wall of the compartment. A rouge compact 61 and a powder compact 62 are held in their respective compartments by split rings 63 and 64, which are formed with circumferentially extending corrugations, the extreme edges of these rings meeting the peripheral walls of the compartments some distance from the flat bottoms thereof to wedgily secure the compacts in place. The rouge compact retaining ring 63 is formed with a spring finger 65 cut from the ring and bent back close to the ring, and a rouge pad 66 is connected to a ring 67 by a tape 68, sewed to the pad and ring as shown in Fig. 13, so that the ring can be hooked over the spring finger 65 to retain the pad in place.

As shown in Figs. 10 and 12 the mirror frame 55 may be latched in registry with the upper compartment 48 by slightly hooked circumferentially extending projections 69 and 70, the former being cut from the flange 56 and bent to extend perpendicularly to the frame 55, and the latter being formed on the upper member of the hinge 51. And, as shown in Fig. 14, the upper member of the hinge may be corrugated to form a recess 71 therebetween, to receive a projection 72 on the mirror frame 55, similar to the projection 69 shown in Fig. 12 but without the circumferentially extending hooked end.

In using the vanity case shown in Figs. 1 to 3, the case is unlatched by swinging the mirror away from its position in registry with the upper compartment, as shown in Fig. 1, to free the projection 23 from the inside of the bead. The case may then be opened and, the mirror being swung about its pivot to a position in extension of the upper compartment away from the hinge 13, and the upper compartment and mirror being swung upwardly until the mirror and the upper and lower compartments are in alignment and facing the user, as shown in Fig. 2, the case as a whole can be conveniently held in one hand during use. The case shown in Figs. 6 to 9 is unlatched by compressing the edge of the lower compartment toward the hinge 40, and the mirror is slid to its position in extension of the upper compartment away from the hinge; and the manner of using the case shown in Fig. 130

10 will be apparent from the description of the structure shown in Figs. 1 to 3, after it is unlatched by disengaging the projection 52 from the recess 51 in the usual 5 manner.

15 It will be apparent that, if desired, the compartments may be hinged so that they can be swung relatively only a little more than ninety degrees to the position shown 10 in Fig. 2, and that in place of a framed mirror a metallic mirror may be used with its latching projection integral therewith and its pivot pin secured to it in any suitable manner.

15 Several embodiments of the invention having been shown and described, it will be understood that the changes suggested herein as well as other alterations in the details of construction may be made without departing 20 from the spirit of the invention which is defined in the following claims.

The invention having been shown and described, what is claimed is:—

25 1. A vanity case comprising upper and lower compartments having a hinge connection, and a downwardly facing mirror secured to said upper compartment exteriorly thereof and movable relative to said compartment to a position in extension of 30 said upper compartment away from said hinge connection.

35 2. A vanity case comprising upper and lower compartments having a hinge connection, and a mirror pivoted to one of said compartments adjacent the edge thereof and remote from said hinge connection, to swing substantially in the plane of said compartment.

3. A vanity case comprising opposed members normally facing each other to form a closed case, hinge means connecting said members, and a mirror carried exteriorly by one of said members and movable to a position in extension of said member away from said hinge means, whereby said mirror and said members may be positioned in alinement facing in the same direction. 40

4. A vanity case comprising a pair of members hinged together to form a case, a mirror movably secured to one of said members, and means controlled by movement of said mirror for latching said members in closed position. 45

5. A vanity case comprising a pair of members adapted to form a closed case, a hinge connecting said members, a mirror pivotally carried by one of said members and movable to a position in registry with said member, and means on said mirror and said hinge cooperating to latch said mirror 60 in such position. 55

6. A vanity case comprising a compact receiving compartment open on one face, a cover for said compartment, and a mirror facing in the same direction as said cover and secured thereto, said mirror being movable from a position in registry with said cover to a position in extension thereof. 65

7. A vanity case comprising a lower compartment, an upper compartment, a compact in said upper compartment, a ring wedged into said upper compartment for retaining said compact therein, and a puff retaining finger integral with said ring. 70

In testimony whereof I affix my signature. 75
HARRY R. BARR.
